(57) **CLAIM**

The ornamental design for a link member for nursing bra closure, as shown and described.

DESCRIPTION

FIG. 1 is a perspective top front view of the link member for a nursing bra closure;

FIG. 2 is a perspective bottom rear view of the link member for a nursing bra closure as shown in FIG. 1;

FIG. 3 is a front view of the link member for a nursing bra closure as shown in FIG. 1;

FIG. 4 is a rear view of the link member for a nursing bra closure as shown in FIG. 1;

FIG. 5 is a top view of the link member for a nursing bra closure as shown in FIG. 1;

FIG. 6 is a bottom view of the link member for a nursing bra closure as shown in FIG. 1;

FIG. 7 is a left side view of the link member for a nursing bra closure as shown in FIG. 1; and,

FIG. 8 is a right side view of the link member for a nursing bra closure as shown in FIG. 1.
